DESIGN FOR A COMBINED HAT AND HAIR ROLL

Elizabeth Y. Simon, New York, N. Y.

Application August 21, 1941, Serial No. 102,980

Term of patent 3½ years

To all whom it may concern:

Be it known that I, Elizabeth Y. Simon, a citizen of the United States, residing at New York city, in the county and State of New York, have invented a new, original, and ornamental Design for a Combined Hat and Hair Roll, of which the following is a specification, reference being had to the accompanying drawing, forming part thereof.

Fig. 1 is a side view of a combined hat and hair roll, showing my new design.

Fig. 2 is a rear perspective view thereof.

The dominant features of the design reside in the portions shown in full lines.

I claim:

The ornamental design for a combined hat and hair roll, substantially as shown and described.

ELIZABETH Y. SIMON.
